CLAIM

The ornamental design for a compartment and console with controls for a recovery vehicle, as shown and described.

DESCRIPTION

FIG. 1 is a perspective view of a compartment and console with controls for a recovery vehicle showing our new design; FIG. 2 is a front, side and top perspective view of the compartment and console with controls for a recovery vehicle shown in FIG. 1; FIG. 3 is a front perspective view of the compartment and console with controls for a recovery vehicle shown in FIG. 1; FIG. 4 is a top perspective view of the compartment and console with controls for a recovery vehicle shown in FIG. 1; FIG. 5 is a right-side side perspective view of the compartment and console shown in FIG. 1; FIG. 6 is a left-side side perspective view of the compartment and console shown in FIG. 1; FIG. 7 is a rear perspective view of the compartment shown in (e.g.) FIG. 5; and, FIG. 8 is a bottom view of the compartment and console shown in the closed position.

In the drawings, the broken lines depict portions of the article and a vehicle that form no part of the claimed design.

The ornamental design for a compartment with a support base mounting a console with controls (e.g., integrated hydraulic and electrical controls) for use in controlling functions of

vehicles used to recover disabled vehicles, such as heavy-duty wreckers, as shown and described in the drawings.
